(57) **CLAIM**

The ornamental design for wireless charger with sockets, as shown and described.

DESCRIPTION

FIG. 1 is a perspective view of a wireless charger with sockets, showing my new design;

FIG. 2 is another perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof; and,

FIG. 9 is an enlarged view of the delineated region 9 in FIG. 2.

The wireless charger with sockets is shown with a symbolic break in its length. The appearance of any portion of the article between the break lines forms no part of the claimed design. The broken lines in the drawings depict portions of the wireless charger with sockets and form no part of the claimed design.
